DESIGN FOR AN EMBOSSED LEATHER

Hyman Singer, New York, N. Y., assignor to Eleso Leather Embossing Co., Inc., New York,
N. Y., a corporation of New York

Application April 26, 1937, Serial No. 68,972

Term of patent 3½ years

To all whom it may concern:

Be it known that I, Hyman Singer, a citizen of the United States, residing at 426 Amboy Street, in the county of Kings and city and State of New York, have invented a new, original, and ornamental Design for an Embossed Leather, of which the following is a specification, reference being had to the accompanying drawing constituting a part thereof.

The figure is a plan view of a piece of the embossed leather showing my new design.

I claim:

The ornamental design for an embossed leather substantially as shown.

HYMAN SINGER.
